UNITED STATES PATENT OFFICE.

ROBERT F. GOLDEN, OF SOUTH ORANGE, NEW JERSEY, ASSIGNOR TO THE NATIONAL LOCK WASHER COMPANY, OF NEWARK, NEW JERSEY, A CORPORATION OF NEW JERSEY.

SPRING WASHER.

Application filed May 8, 1923. Serial No. 637,432.

To all whom it may concern:

Be it known that I, ROBERT F. GOLDEN, a citizen of the United States, residing at South Orange, in the county of Essex and 5 State of New Jersey, have invented certain new and useful Improvements in Spring Washers; and I do declare the following to be a full, clear, and exact description of the invention, such as will enable others 10 skilled in the art to which it appertains to make and use the same.

My invention relates to improvements in spring washers of the split-ring type, and it consists of certain novel parts and combinations of parts particularly pointed out in 15 the claims concluding these specifications.

In spring-washers of the split-ring type as heretofore constructed, whether they were of the plain spiral type or of the corrugated or deformed type, and whether the 20 material was rectangular in cross-section or of other shapes (as, for example, of key-stone shape) the material transversely has been in planes substantially at right angles 25 to the axis of the spiral, so that, when the spring-washer was compressed between parallel surfaces, all portions of the width were deflected an equal distance. The inner circumference of a spring-washer is con- 30 siderably shorter than the outer circumference and, since the strains set up in deflecting a rod, or a section of a rod, are directly proportional to the distance it is deflected and inversely proportional to its 35 length (that is to say, the strains increase as the distance deflected increases, and increase as the length of the rod decreases) it follows that in such spring-washers the material at and near the inner circumfer- 40 ence was subject to greater strains than the material at and near the outer circumfer- ence; whereas, in order to secure maximum efficiency, all portions of the material should be subject to the same strains, as 45 otherwise the elastic limit of one portion will be exceeded before that of another portion is reached. In order to increase the efficiency of the spring-washer, I so fashion the material composing it that the 50 inner and shorter circumference of the spring-washer will, in the act of being compressed between parallel surfaces, be deflected a less distance than the outer and longer circumference, so that all portions of

the material will be subject to substantially the same strains.

In a spring-washer of the split-ring type, either spiral or deformed, or both spiral and deformed, be subject to compression between parallel surfaces, it will be completely flattened out without developing any strains which tend to compress or crimp the metal which is inside the medial line of the spring-washer, and without developing any strains which tend to expand or rupture the metal which is outside the medial line of the spring-washer, as would be the case if the spring-washer were a continuous one, or if the ends of the spring-washer were not free to move, as they are in the split-ring type of spring-washer. Such flattened condition I will call the ultimate plane of compression. By forming a spring-washer of the split-ring type so that the inner and shorter circumference departs from the ultimate plane of compression by an amount less than does the outer and longer circumference, the strains in all portions of the material throughout its width may be substantially equalized. In such a spring-washer the spirality of the inner circumference is less than that of the outer circumference—or, in other words, the inner circumference in approaching the ultimate plane of compression moves a shorter distance than does the outer circumference. In so fashioning the spring-washer, I prefer to make the material transversely in planes converging to a common point on the axis of the washer, although this is not necessary to the embodiment of my invention in its broader aspects.

Referring to the drawings, Figure 1 is an elevation in perspective of a spring-washer of a plain spiral split-ring type constructed in accordance with the preferred form of my invention.

Figure 2 is a plan view of the same.

Figure 3 is a section on the line 3—3 of Figure 2.

Figure 4 is a section on the line 4—4 of Figure 2.

Figure 5 is an elevation in perspective of a spring-washer similar to that shown in Figure 1, but with the material formed in a series of corrugations or deformations.

Figure 6 is a plan view of the structure shown in Figure 5.

Figure 7 is a section on the line 7—7 of Figure 6.

Figure 8 is a section on the line 8—8 of Figure 6.

6 In each of the figures, 9 is a spring-washer of the split-ring type. A—A is the axis of the spring-washer. 10, 10 is the inner circumference, and 11, 11 the outer circumference of the spring-washer. a—b 10 is the ultimate plane of compression. c—d and e—d and f—d are planes of the material of the spring-washer taken at different points, and it will be observed (although this is not necessary, to my invention in 15 its broader aspects) that these planes all meet at a common point on the axis A—A. The essential thing is that, in a practical sense, the inner circumference of the spring-washer, as is clearly shown in the drawings, in being deflected to or toward the ultimate plane of compression, moves a shorter distance than does the outer circumference. In other words, considering 20 the spring-washer as made up of a series 25 of parallel rods which are progressively shorter as they approach the inner circum-

ference, and are progressively longer as they approach the outer circumference, these rods, in being deflected toward or to the plane of ultimate compression, are deflected distances substantially directly proportional to their lengths. 30

What I claim is:

1. A spring-washer of the split-ring type, the inner circumference of which departs 35 from the ultimate plane of compression a distance less than does the outer circumference.

2. A spring-washer of the split-ring type, the material transversely being in planes 40 which when projected inwardly substantially meet at an apex located on the axis thereof.

3. A spiral spring-washer of the split-ring type, the material thereof transversely 45 being so formed that the pitch of those spiral lines contained in the inner circumference is less than the pitch of those spiral lines contained in the outer circumference.

In testimony whereof I affix my signature hereto.

ROBERT F. GOLDEN.
